CLAIM

The ornamental design for a digital multi meter, as shown and described.

DESCRIPTION

FIG. 1 is a front perspective view of a digital multi meter. FIG. 2 is a rear perspective view of the digital multi meter; FIG. 3 is a front planar view of the digital multi meter; FIG. 4 is a rear planar view of the digital multi meter; FIG. 5 is a left side planar view of the digital multi meter; FIG. 6 is a right side planar view of the digital multi meter; FIG. 7 is a top planar view of the digital multi meter; FIG. 8 is a bottom planar view of the digital multi meter; and, FIG. 9 is a front planar view of the digital multi meter. The broken line showing of structural features is included for the purpose of illustrating non-claimed subject matter and forms no part of the claimed design.
